WELL PACKER

Albert Pranger, Dallas, Tex., assignor to The
Guiberson Corporation, Dallas, Tex., a corpora-
tion of Delaware

Application June 8, 1936, Serial No. 84,041

3 Claims. (Cl. 166—12)

This invention relates to well packers and more particularly to a control head type of packer for oil wells and the like.

An important object of the invention is to produce an improved packer for oil wells and the like which can be applied in flowing wells against high fluid and gas pressures.

A particular object of the invention is to provide an improved construction whereby the fluid 10 of the well will run smoothly and in increased volume around the valve head and between the valve head and valve seat to keep said parts clear of particles of hard and gritty substances 15 whereby to prevent cutting of the valve and valve seat and at the same time allowing maximum travel of the tubing through the packer for the setting of the packing members before the closing of the valve is accomplished.

Another object is to secure the better and more 20 dependable sealing effect between the valve and valve seat.

A further object is to provide improved means for holding together, as one assembly on the packer mandrel tube, the valve seat, rubber 25 packing members, spacer, thimble, slip head, slips, links, cage and friction spring members, whereby to make the whole packer assembly relatively short and compact and at the same time permit of a long valve lift and maximum travel of 30 the tubing through the packer in placing and setting it in the well casing.

Still another object of the invention is to improve the mandrel structure whereby not only to strengthen the mandrel tube but to provide a stop 35 under the slip head so as to normally support the packer assembly and act as a recovery ring, permitting jarring, if necessary.

Other objects and advantages to be attained will hereinafter more fully appear in the following specification.

The invention will be more readily understood from a reading of the following specification and by reference to the accompanying drawings, in which an example of the invention is shown, and 45 wherein:

Figure 1 is a view partly in elevation and partly in longitudinal section of the upper portion of a packer constructed in accordance with the invention, the parts being in their normal positions and condition and the packer being shown in a well casing;

Figure 2 is a similar view showing the lower portion of the packer;

Figure 3 is a view similar to Figure 1, but showing the parts in their closed position and con-

dition and the rubber packing members shown compressed and expanded transversely into sealing engagement with the inner face of the well casing;

Figure 4 is a section taken substantially on the line 4—4 of Figure 3; and

Figure 5 is a section taken on or about the line 5—5 of Figure 3.

Referring now to the drawings, the numeral 10 designates the well casing or tubular lining 10 which is usually provided in the well hole and through which the product from the well is taken in the usual manner.

The packer illustrated in the drawings comprises a body tube or mandrel 11 of considerably 15 longer length than the rubber packing members and cooperating metal parts assembly and also the slip mounting and anchor cage assemblies, for a purpose which will be more fully hereinafter described. The lower end portion of the body 20 tube or mandrel 11 is attached to a standard coupling 12 which, in practice, is employed to connect the mandrel 11 with anchor tubing (not shown) of various lengths, in some cases.

Sleeved to slide freely on the mandrel 11 is 25 a tubular cage 13, said cage tube 13 extending down to near the coupling 12 and having a longitudinal slot 14 extending nearly the entire length thereof, said slot 14 communicating at its upper end with the horizontal short slot 15 30 through which projects a gudgeon or key stud 16 provided on said mandrel 11. Normally, when said gudgeon or key stud 16 is located in the transverse slot 15 said cage tube 13 obviously moves endwise with said mandrel 11 but if the 35 mandrel 11 is turned with relation to the cage tube 13 to bring the gudgeon or key stud 16 in line with the longitudinal slot 14 endwise movement of said mandrel 11 and cage sleeve 13 is 40 possible independently of each other. Near the upper end of the cage tube 13 are peripheral lugs 17 (preferably three in triangular spaced relation to each other) to each of which is secured the upper end portion of an outwardly bowed spring 45 member 18, said spring members 18 being attached at their lower ends to a spring rest 19 in the form of a collar which is sleeved to slide freely on said cage tube 13. The outwardly bowed cage springs 18 have a normal set so that the 50 bilged portions thereof always press against the adjacent inner face portions of the well casing 10 and with sufficient frictional resistance to hold the cage 13 from both endwise and rotative movement unless said cage 13 is interlocked with 55

said mandrel 11 by the engagement of the gudgeon or key stud 16 in the slots 14 and 15.

Bifurcated lugs 20 are provided on the upper end portion of the cage 13, to which the lower end portions of link members 21 are pivotally attached, as at 22, said link members being pivotally attached at their upper ends, as at 23 to lugs 24 provided on the lower end portions of slips 25.

The outer faces of the slips 25 are provided with the usual sharpened gripping portions 26 to engage the inner face of the well casing 10 during the process of setting the packer in said casing. The slips have inclined inner face portions to slide upon correspondingly inclined portions of the slip head 27, said slip head 27 having a marginally undercut rib 28 on its inclined portion and the slip being correspondingly provided with an undercut groove to slidably fit said undercut rib. In each of the ribbed portions 28 of the slip heads 27 is provided a median longitudinal groove 29 into which is projected a hardened pin 30 provided on the cooperating slip 25. By the provision of the slot pin arrangement 29, 30, the slips are freely movable on the dove-tailed or marginally undercut ribs 28 of the slip head 27, but the downward movement of the slips 25 on the slip head 27, or, upward movement of the slip head relative to the slip, is limited by the engagement of said pin 30 with the lower end of the slot or groove 29.

The slip head 27 is slidably fitted on the body tube or mandrel 11 and said mandrel is provided with an annular shoulder 31 upon which the lower end of the slip head 27 normally rests, and by which provision together with the slot and pin connection 29, 30 between the slip head and slips; the cage 13 is normally supported in suspended relation from the slips 25 by the links 21. Preferably, the shoulder 31 on the mandrel 11 is provided by the upper end of a supplemental mandrel tube or tubular member 32 which is sleeved on said mandrel 11 and welded thereto, by which construction not only is the shoulder 31 conveniently provided but the lower end portion of the mandrel 11 is materially strengthened.

The upper end portion of the slip head 27 is counterbored and internally screw-threaded, as at 33, where it is secured to a correspondingly externally screw-threaded reduced lower end portion 34 of a thimble 35. The thimble 35 is provided with a series of apertures 36 affording communication between by-pass or fluid flow passages internally of the packer and the space between the exterior of the packer and the well casing 10. In the upper end portion of the thimble 35 is an annular channel formed by a cylindrical inner wall portion 37 and a spaced outer upstanding flange 38, into which channel is fitted the lower portion 39 of a rubber packing member 40 whose upper end portion 41 is fitted in a similar channel provided in a spacer member 42. Said channel of the spacer member 42 is formed by the lower inner cylindrical portion 43 and an outer downwardly disposed annular flange 44 on said spacer member 42. The spacer member 42 is provided with an upper channel formed by its inner cylindrical portion 45 and an outer upwardly disposed annular flange 46, in which upper channel the lower end portion 47 of a second rubber packer member 48 is fitted, the upper end portion 49 of said packer member 48 being fitted in an annular groove provided therefor in a valve seat collar 50, the channel in which the portion 49 is fitted being provided

by the lower inner cylindrical portion 51 and outer downwardly disposed annular flange 52 of said valve seat collar 50.

Normally, the meeting ends of the cylindrical supporting portions 51, 45, 43 and 37, of the metal members which support the upper packing members 40 and 48, respectively, are spaced apart a limited distance to permit relative endwise movement of said metal supporting members 50, 42 and 35, whereby to permit endwise compression of said packing members 40 and 48 which causes lateral or transverse expansion of said members to make them contact peripherally with the inner face of the well casing 10, upon the occurrence of which said spaced ends of the portions 51, 45, 43 and 37, meet in contact with each other, thereby preventing further compression of said packing members 40 and 48.

To support the middle portions of the rubber packing members 40 and 48 and prevent said portions from being squeezed and bulged into the spaces between the ends of the cylindrical portions 51, 45, 43 and 37, of the metal supporting members of the packer assembly, metal bushing rings 53 are embedded in said packing members 40 and 48, said bushing rings 53 being of a width wider than the distance between the spaced ends of the parts 51, 45, 43 and 37; and to hold said packing rubber assembly together, that is to say, to prevent endwise separation from their normal positions, the parts 50, 48, 42, 40 and 35 are linked together by longitudinally elongated semi-cylindrical plates 54 having flanges 55, 56, at their opposite ends, said plates being interposed between the mandrel tube 11 and the respective metal parts 50, 42 and 35 of the packer assembly and said parts 50, 42 and 35, respectively, being provided with longitudinally recessed portions 57 to accommodate said plates 54 and hold them against rotative movement independently of said parts 50, 42 and 35. Said plates 54, of which there are preferably three arranged in triangular relation to each other, space said parts 50, 42 and 35 concentrically from the mandrel 11 whereby to provide three fluid flow passages 58 between said parts, the flanged end portions 55 of said plates 54 being fitted in recesses 59 provided therefor in said valve seat collar 50 and the lower flanged portions 56 of said plates 54 being engaged under a shoulder 56' provided therefor on the thimble 35, it being this engagement of said flanged portions 55 and 56 with the parts 50 and 35 that enables the plate members 54 to hold the packer assembly together.

At the upper end of the valve seat collar 50 is an internal bevelled seat portion 59 for the reception of a corresponding seat portion 60 of a valve head 61 provided on the lower end portion of a coupling member 62 into the lower end portion of which the upper end portion 11' of the mandrel tube 11 is secured by screw-threaded attachment.

In order to secure a more perfect sealing effect when the portion 60 of the valve head 61 enters the seat portion 59 of the valve seat collar 50, it is preferable to provide said portion 60 of the valve head 61 with an annular insert 63 of a resilient material, preferably "Duprene", a now well known product having the resilient qualities of rubber with the further advantage of being resistant to the action of oils and fluids detrimental and destructive to the ordinary rubber materials.

In practice, in the normal relative positions of

the parts of the packer previous to its application in the well and while it is being placed in the well and removed therefrom, the mandrel 11 is relatively elongated so that, normally, the valve

5 head 61 is a considerable distance above the valve seat collar 50 which is a part of the packing rubber assembly, this relative elongation of the mandrel 11 between the coupling 62 and valve seat collar 50 gives a longer stroke in the
10 closing of the valve than is ordinarily provided in packer structures, whereby to prevent nozzleing, which is of material advantage because more time is given for the flowing fluid in the well to wash the seating portions of the valve
15 seat collar 50 and valve head 61 whereby to minimize the possibility of the lodgement on said seating portions of particles of hard substances which might prevent proper seating of the valve or injure the valve seating faces. There
20 is a further advantage in the increased stroke of the mandrel 11 in that greater force and effect is attained should occasion require that the packer be jarred in running it into the well or recovering it from the well.

25 In applying the packer to a well casing, the parts being in normal position and the gudgeon or key stud 16 of the mandrel 11 being in the horizontal slot 15 of the cage 13, and the string of stem tubing (not shown) being attached to
30 the upper end portion of the collar 62, the packer is lowered into the well until the rubber packing assembly portion is approximately in a position 12 inches to 18 inches above the point at which it is desired to pack off the casing. As the spring
35 elements 18, due to their engagement with the well casing 10, hold the cage 13 from turning the tubing is given a part turn to the left so as to move the gudgeon or key stud 16 out of the horizontal slot 15 and into line with the vertically
40 elongated slot 14 in the cage 13. The tubing is then further lowered and as the cage 13 is held by the springs 18 the slip head 27, under the weight of the rubber packing assembly thereabove and attached thereto, through the thimble 35, as at 34, moves downwardly with the mandrel 11 and with relation to the slips 25 whereby to spread said slips outwardly into contact with the adjacent wall portion of the well casing 10. As soon as the slip head 27 has
45 wedged the slips 25 into firm gripping contact with the well casing 10, further downward movement of the rubber packing assembly is prevented, whereupon the mandrel 11 continues on downwardly until the valve head 61 engages the
50 valve seat collar 50 at the upper end of the rubber packing assembly. After the valve head 61 is seated on the valve seat collar 50 the weight of the string of tubing above the collar 62 or the force transmitted through said tubing causes
55 the endwise compression of the rubber packing members 48 and 40 and their outward expansion into peripheral contact with the adjacent face portions of the well casing 10 whereby the well casing 10 is packed and the flow of the fluid
60 through the by-pass passages of the packer is stopped because of the seating of the valve head 61 on the valve seat collar 50.

To withdraw the packer or raise it to a higher position in the well casing 10 it is only necessary to lift the string of tubing and, of course, correspondingly lift the attached mandrel 11, until its external annular shoulder 31 engages the lower end of the slip head 27, whereupon the slip head 27 and the packer assembly thereabove move upwardly with said mandrel 11,

thereby releasing the slip head from its wedging action upon the slips 25 which are held down by the springs 18 of the cage assembly 13 until the pin or stud 30 on the slip heads is engaged by the lower end of the slots 29 of the slip head, 5 upon the happening of which the cage 13 moves upwardly with the other parts because of the link connection 21 between the upper end of the cage 13 and said slips 25.

Should it be desired to reset the packer at a 10 lower position in the well casing 10 the string of tubing and the mandrel 11 are raised as just above described until the gudgeon 16 has reached the upper end of the slot 14 in the cage 13, whereupon the tubing is turned to the right to 15 move said gudgeon into the horizontal slot 15 of the cage 13. The tubing is then lowered to bring the packer to the desired lower position where it is reset in the same manner in which it was originally set in the casing 10.

For the attachment of a fishing tool, should 20 occasion require, the coupling member 62, as shown, is provided with a series of annular shoulder portions 64. It is here further noted, that the structure may be modified in many respects within the spirit and scope of the invention as defined in the appended claims. The invention, therefore, is not limited to the specific construction and arrangement shown. For example, a larger number of the rubber packing members 40, 48, may obviously be employed in the packer assembly, or, in some cases, only a single rubber member; and, of course, the tie plates 54 will be accordingly increased or decreased in length, as the case may be, and the 30 intermediate spacer members 42 correspondingly increased or decreased in number.

What I claim and desire to secure by Letters Patent, is:

1. In a well packer, a mandrel tube having 40 provision at its upper end for attachment to an operating extension, an annular valve head on said mandrel, near its upper end, a packer assembly sleeved on said mandrel with fluid flow passageways therebetween, said packer assembly comprising an upper valve seat collar and a lower thimble member, upper and lower rubber packer members secured respectively to the upper valve seat collar and the lower thimble member, an annular spacer member interposed 45 between said upper and lower rubber packer members and supporting the upper and lower ends of said packer members, respectively, the meeting ends of said annular spacer member and said upper valve seat collar and said lower thimble member being spaced apart under the support of said rubber packer members in their 50 normal form, said rubber packer members being endwise compressible and transversely expandible with such compression and expansion being 55 limited by the meeting of the ends of said spacer member and said valve seat collar and thimble member, longitudinally disposed tie members interposed between said mandrel tube and said 60 packer assembly whereby to hold said assembly 65 in spaced concentric relation to said mandrel tube, said longitudinal tie members being engaged at their upper and lower ends, respectively, with said upper valve seat collar and said lower thimble member whereby to hold said packer assembly 70 in its normal extended position but permitting endwise movement of the elements of said assembly whereby to compress and expand said rubber packing members, said thimble member having by-pass opening affording communication 75

between the internal flow passageways of said packer and the space in the well casing outside of the packer, a slip head attached at its upper end to said thimble member whereby the one is 5 movable by and with the other and the packer assembly is supported on said slip heads, means on said mandrel for releasably supporting said slip head in its normal raised position, slips slidably supported on said slip head whereby upon 10 relative endwise movement of the slip head and slips said slips are wedged into gripping contact with the well casing, an anchor cage slidably endwise and rotatably on said mandrel and having provision for frictional engagement with 15 the well casing, a pivotal link connection between said anchor cage and said slips, and means operable upon the relative rotation of said mandrel and said anchor cage for locking them against relative independent endwise movement 20 and for releasing them from said lock, at will.

2. In a well packer, a packing rubber assembly in combination with a mandrel, said mandrel having an annular valve head thereon, said packer assembly comprising an upper valve seat collar having an annular seating portion at its 25 upper end for engagement of the valve head on said mandrel, said valve seat collar having an annular channel on its underside, a thimble member having an annular channel on its upper side, an intermediate spacer member having correspondence channels on its upper and lower sides, upper and lower rubber packing members having their upper and lower ends respectively fitted in the channels of said upper valve seat 30 collar, said lower thimble member and said intermediate spacer member, the meeting ends of the inner portions of said collar, thimble and spacer member being normally spaced apart and meeting upon endwise compression and lateral 35 expansion of said rubber packing members, whereby to restrict the compression and expansion of said rubber packer members, longitudinal tie members interposed between said mandrel and said packer assembly elements engageable at 40 their upper and lower ends with said upper valve seat collar and said lower thimble member whereby to hold said assembly together in normal endwise relation but permitting movement of the elements toward each other whereby to effect the compression and expansion of said rubber packing members, by-pass openings in said 45 thimble member to establish communication be-

tween flow passageways extending through the interior of the packer and the space between the well casing and exterior of the packer, and casing engaging anchor and wedge slip means movably supported on said mandrel below said packer assembly, whereby, upon the downward movement of said mandrel from normal position, said anchor and wedge slip means initially engage the well casing and whereby, upon engagement of the valve head on said mandrel with the valve 10 seat collar of the packer assembly, said packer assembly is compressed to expand the rubber packing members in sealing engagement with the adjacent face portions of the well casing.

3. In a well packer, a packing assembly comprising endwise movable metal annular members, the upper member having an annular valve seat at its upper end and an annular channel in its lower end portion, the lower member comprising a thimble having an annular channel 15 in its upper portion, and its lower end attached to a slip head, a spacer member intermediate said upper and lower members, said spacer member having corresponding annular channels at its upper and lower portions, rubber packer members having reduced upper and lower end portions fitted respectively in the channels of said annular metal members, said packer members having outwardly bilged middle portions, the inner wall portions of said metal members of the 20 assembly having their meeting end portions normally spaced apart, annular members surrounding the spaced meeting portions of said metal members to support the upper packing members and prevent the deformation of said packer members and bulging thereof into the spaces between said metal members, said metal members meeting with their said inner portions in contact when moved toward each other under sufficient 25 force to compress and outwardly expand said rubber packing members whereby to limit such compression and expansion and support said members in such condition, longitudinal tie means for holding said rubber packer assembly together but permitting relative movement of the parts 30 to effect the compression and expansion of said rubber packing members, with an anchor means movable on said mandrel and supported from said packer assembly, and means for interlocking said mandrel and the anchor means and releasing 35 them from such interlock, at will.

ALBERT PRANGER.
